PORTABLE COMBINATION IRONING BOARD
AND LUGGAGE CASE

Mary R. O'Buckley, Horseheads, N.Y.

Filed June 20, 1958, Ser. No. 743,342

1 Claim. (Cl. 38—112)

This invention relates to collapsible or folding portable ironing boards and containers, and in particular a plurality of hinged panels designed to be folded to provide a carrier for luggage and which, when opened to an extended position provides an ironing board.

The purpose of this invention is to provide means whereby a traveler may readily carry an ironing board in his luggage continuously.

Various types of devices have been provided for improvising ironing boards in hotel and motel rooms and also in rooming houses and small apartments, however, such devices are designed for temporary use and have not been found satisfactory.

With this thought in mind this invention contemplates an ironing board formed with a plurality of hinged panels with means for retaining the panels in an extended position and in spaced relation to a surface upon which the ironing board is positioned and in which the panels are designed to be folded to provide a carrier for luggage and the like.

The object of this invention is, therefore, to provide a sectional ironing board which may be used as a luggage carrier for traveling, and which may readily be set up for ironing.

Another object of the invention is to provide a collapsible ironing board that may be folded to provide a luggage carrier or set up for ironing in which the parts are rigidly held in extended positions when the device is used for ironing.

Another important object of the invention is to provide a folding ironing board which may be used as a luggage carrier or the like in which the ironing board is spaced above a telescoping base when set up for use.

It is yet another object of the invention to provide a collapsible ironing board that may be folded to provide a luggage carrier in which the parts are of comparatively light weight.

A further object of the invention is to provide an ironing board formed of hinged panels in which the parts may be set up for use by the average layman.

A still further object is to provide a combination ironing board and luggage carrier which is of a simple and economical construction.

With these and other objects and advantages in view the invention embodies a rectangular-shaped base panel, end panels hinged to ends of the base panel, a side panel complementary to the base panel and hinged to one of the end panels, a nose panel hinged to the extended end of the side panel and formed to fold against the inner surface thereof, pins slidably mounted in tubes or rolls at the edges of the panels for retaining the panels in extended positions, and a telescoping frame connected by legs to the inner surface of the base panel for supporting the ironing board in an extended position.

Other features and advantages of the invention will appear from the following description taken in connection with the drawings, wherein:

2

Figure 1 is a perspective view showing the collapsible ironing board folded to provide a luggage carrier.

Figure 2 is a perspective view showing the device extended to provide an ironing board, and looking toward the under surface thereof.

Figure 3 is a side elevational view of the combination ironing board and luggage carrier with parts broken away showing a longitudinal section through the device.

Figure 4 is a cross section through the base panel of 10 the ironing board and luggage carrier taken on line 4—4 of Figure 2 with the parts shown on an enlarged scale, and showing, in particular, the inwardly inclined legs of the telescoping support frame, in broken lines.

Figure 5 is a longitudinal section through the intermediate part of the ironing board with the parts extended and showing, in particular, one of the locking pins or keys of the device.

Figure 6 is a perspective view with the parts shown on an enlarged scale illustrating the keys or plates for retaining the nose panel in an extended position when the device is used for an ironing board.

Figure 7 is a cross section through the side panel taken on line 7—7 of Figure 6 showing the mounting of one of the keys or plates for retaining the nose panel extended.

While one embodiment of the invention is illustrated in the above-referred-to drawings, it is to be understood that they are merely for the purpose of illustration, and that various changes in construction may be resorted to 30 in the course of manufacture in order that the invention may be utilized to the best advantage according to circumstances which may arise, without in any manner departing from the spirit and intention of the device, which is to be limited only in accordance with the appended 35 claim. And while there is stated the primary field of utility of the invention, it remains obvious that it may be employed in any other capacity wherein it may be found applicable.

In the accompanying drawings, and in the following 40 specification the same reference characters are used to designate the same parts and elements throughout, and in which the numeral 10 refers to the invention in its entirety, numeral 12 indicating a rectangular-shaped base panel, numeral 14 a similarly shaped side panel of the same size and shape as that of the base panel, numeral 16 a nose panel hinged to the extended end of the side panel, numeral 18 a first end panel positioned between the panels 12 and 14, numeral 20 a second end panel hinged to the base panel 12, numerals 22 and 24 side 45 walls hinged to ends of the end panel 20, numerals 26 and 28 tubes extended from legs 30 secured to the under surface of the base panel 12, numeral 32 telescoping tubes mounted in the tubes 26 and 28, and numerals 34 and 36 rods slidably mounted in the tubes 32 and connected by a cross rod 38 on which a sleeve 40 is positioned, thereby providing a U-shaped support.

The sides of the base panel 12 are provided with flanges 42 and 44 and tubes 46 and 48 are nested inside of the flanges, as shown in Figure 4. The legs 30 are provided with sections 50 and 52, respectively, which are positioned inside of the tubes 46 and 48, and the tubes are secured to the base plate by brazing, welding, or other suitable means.

The end panel 20, on which a handle 54 is mounted 55 by straps 56 and 58 is connected to the base panel 12 by a piano hinge 60 and the side walls 22 and 24 are connected to ends of the end panel 20 by similar hinges 62 and 64. The opposite end of the base panel 12 is connected to the end panel 18 by a piano hinge 66 and 60 the opposite side of the end panel 18 is connected to the side panel 14 by a similar hinge 68. The nose panel 16 is connected to side panel 14 by a piano hinge 70.

The sides of the nose panel 16 are provided with arcuate recesses 72 and 74 whereby the extended end of the nose panel is patterned to correspond with a conventional ironing board.

The intermediate panels are retained in extended positions by sliding bolts or pins 76 that are actuated by knobs 78 which extend through slots 80 in the tubes, as illustrated in Figure 5. The ends of the tubes are provided with beveled surfaces 82 that facilitate folding to an angle of 90°. The tubes 46 and 48 of the base panel are aligned with tubes 84 and 86 of the end panel 18, and the tubes 84 and 86 are aligned with tubes 88 and 90 on the edges of the side panel 14. By sliding the pins across the connecting points of the panels the panels are rigidly retained in extended positions.

The hinge plate 92 of the hinge 70 connecting the nose panel 16 to the side panel 14 is provided with offset end sections 94 which extend away from the panel providing sockets into which wing plates 96 extend with the plates in the positions indicated by the broken lines 98, shown in Figure 6. The wing plates 96 are carried on the sides of bolts 100 slidably mounted in the extended ends of the tubes 88 and 90 of the side panel 14. The wing plates 96 are secured to the rods or bolts 100 by studs 102 and in the folded position the wing plates are moved inwardly to the positions indicated by the broken lines 104. In setting up the ironing board the wing plates are drawn outwardly to the positions indicated by the broken lines 106, then turned to the positions against the nose panel and slid inwardly with the ends sliding into the offset sections 94 of the hinge plate 92. With the wing plates in these positions the nose panel 16 is rigidly supported in an extended position for ironing.

Edges of the end panel 18 and side panel 14 are provided with flanges similar to the flanges 42 and 44 of the base panel, the panel 18 having flanges 108 and 110, and the panel 14 having flanges 112 and 114, the flanges being positioned to overlap edges of the side walls 22 and 24 with the parts folded, as shown in Figure 1.

Operation

With the parts folded, as shown in Figure 1, wearing apparel, or the like, may be packed in the carrier and the device transported with other luggage to a hotel or motel room or the like, and should it be desired to use an ironing board, a latch 116 connecting the panel 20 to the side panel 14 is released, and the parts extended, as shown in Figure 2 with the locking keys or pins extended across the connections between the panels and with the wing plates extended into the sockets of the hinge plate 92. The side walls are folded against the end panel 20 and the telescoping rods extended as shown in Figure 3.

In folding the device the wing plates are removed from the sockets of the hinge plate 92 and the nose plate folded against the inner surface of the side panel 14. The pins in the tubes at the edges of the panels are withdrawn, the side walls 22 and 24 positioned behind the flanges 42 and 44 of the base panel, and with the

telescoping base retracted, the flanges of the end panel 18 and side panel 14 are positioned over edges of the side walls, and the latch 116 fastened.

From the foregoing specification it will become apparent that the invention disclosed will adequately accomplish the functions for which it has been designed and in an economical manner, and that its simplicity, accuracy, and ease of operation are such as to provide a relatively inexpensive device, considering what it will accomplish, and that it will find an important place in the art to which it appertains when once placed on the market.

It is thought that persons skilled in the art to which the invention relates will be able to obtain a clear understanding of the invention after considering the description in connection with the drawings. Therefore, a more lengthy description is regarded as unnecessary.

Changes in shape, size, and arrangement of details and parts such as come within the purview of the invention claimed may be resorted to in actual practice, if desired.

Having now described the invention that which is claimed to be new and desired to be procured by Letters Patent, is:

In an ironing board and carrier, the combination which comprises a rectangular-shaped base panel, a first end panel hinged to one end of the base panel, a side panel of the same pattern and size as that of the base panel hinged to the extended edge of the first end panel, an ironing board nose panel hinged to the extended edge of the side panel and patterned to nest against the inner surface of said side panel, a second end panel hinged to the end of the base panel opposite to the end to which the first end panel is hinged, side walls hinged to the ends of said second end panel, the base panel, side panel, nose panel, and first and second end panels being connected by piano hinges providing a smooth outer ironing surface, said base, side, nose, and end panel positioned between the base and side panel having longitudinally disposed registering tubes on under surfaces, pins slidably mounted in the tubes for retaining the panels in extended positions, and a U-shaped frame having telescoping arms mounted on and spaced from the base panel for supporting the ironing board from and in spaced relation to a supporting surface.
